UNITED STATES PATENT OFFICE.

CARL FREDRIK JAKOB FORSELL, OF CLEVELAND, OHIO, ASSIGNOR TO THE NATIONAL CARBON COMPANY, A CORPORATION OF NEW JERSEY.

ELECTRIC FURNACE.

982,420.

Specification of Letters Patent. Patented Jan. 24, 1911.

Application filed July 20, 1908. Serial No. 444,354.

To all whom it may concern:

Be it known that I, CARL FREDRIK JAKOB FORSELL, a subject of the King of Sweden, residing at Cleveland, in the county of Cuyahoga and State of Ohio, have invented a certain new and useful Improvement in Electric Furnaces, of which the following is a full, clear, and exact description.

The object of the present invention is to provide an improvement in electric furnaces which are used for heating articles contained therein, especially furnaces used for such purposes as make it desirable to have all of the articles heated to the same temperature.

A type of the furnace in question is that used for metallizing carbon filaments which is tubular in shape, and it is my purpose to introduce improvements in this furnace which shall render it possible to produce a uniform temperature throughout the working portion of the furnace, thereby avoiding the unequal heat treatment of the articles contained therein.

The above stated object together with certain structural advantages, will be seen to be obtained by the embodiment of my invention described in the following specification with reference to the accompanying drawings in which;

Figure 1 is a plan view of a bank of electric tube furnaces constructed according to my invention. Fig. 2 is an enlarged longitudinal section of a form of my furnace showing the resister tubes held between the water cooled terminals. Fig. 3 is an elevation showing the tube with a packing slot, through which the articles to be treated are inserted. Fig. 4 is a cross-section of the tube showing the packing slot. Fig. 5 is a detail longitudinal section showing a modified form in which a carbon plug or rod is interposed between the end of the resister tube and the water cooled terminal.

I have discovered that in the working of the electric tube furnace hitherto known, there will be a material difference in the character of the articles treated therein so that a uniformity of product is not to be counted upon. This is especially true in the process of metallizing carbon filaments, a process which demands uniformity in the character of the product more than most processes. I have found that the ununiformity in the quality of the filaments packed

in such a tube furnace results in part from the ununiformity of the temperature at the different points of the furnace, and inasmuch, therefore, as the attainment of a uniform temperature throughout that portion of the tube in which filaments are packed would markedly improve the product, it has been my purpose to so construct the furnace that this lack of uniformity in temperature shall not occur. I have obtained this object without necessitating any change in the conventional construction of the furnace terminals or leads, as will appear in the drawings. These resister tubes have heretofore been open throughout, having each end chamfered so as to fit in a carbon bushing within a water cooled terminal to which a heavy electric current is supplied by means of suitable leads fitted thereto. Water cooling is advantageous for the preservation of the leads, but it nevertheless increases the divergence of temperature in the different parts of the furnace. That portion of the tube nearest the end has its heat abstracted by means of the water cooled terminal, while the temperature of the middle zone of the tube may rise to the full value which it should have considering the flow of current and the resistance of the tube.

In my construction, as illustrated, the reference letter A represents the wall of a bank of furnaces having therein oppositely positioned water cooled terminals B with a tapered socket at each end and the outer socket B' having fitted thereto the tapered brass plug B² of the current lead. In the inner socket B³ of each terminal is fitted a carbon bushing C, in which bushings are fitted the chamfered ends of the supporting means for the material to be treated, said means being the container or carbon resister tube D, in that form of construction shown in Fig. 3, or the rods E, in the form shown in Figs. 2 and 5, which rods support the container or resistance tube D. These tube furnaces are preferably, for convenience in charging them, provided with a slot D' cut lengthwise by means of two longitudinal cuts and two transverse cuts at each end thereof, made with a thin steel disk-saw. The strip of carbon thus cut out is subsequently used to close the slot after the packing of the filaments has been completed. Near each end of the tube immediately ad-

5 jacent to the working portion, I cut an annular groove E of a suitable width and depth. In the case of the ordinary carbon tube having, say an effective length of 30 inches with an outside diameter of 2-1/2 inches, a 1/4 inch wall and consequently with an internal diameter of 2 inches, I should make this groove approximately 1 inch wide with a depth of about 3/32 inches, thus increasing 10 the resistance of the tube at this point so that the generation of heat thereabout will be decidedly greater than at any other part of the tube. By properly proportioning the dimensions of the tube and grooves, the heat generated will be sufficient to raise the temperature at the grooves in spite of the loss of heat to the terminals, to the same point attained along the middle section of the tube which has a less resistance. The heat generated 15 at the grooves being sufficient to maintain this temperature, in spite of the loss of heat on account of conduction to the terminals, there will be no loss of heat from the middle or working portion of the tube, except to the surrounding medium, and a uniform temperature will be produced along the full length of this working section. The proper dimensions of the groove, of course, will vary with different materials and for 20 different conditions; and these dimensions should be determined by trial with each material and for each condition before a standard is adopted for that material and condition.

25 35 In view of the fact that tubes are rarely perfectly cylindrical, the cutting of a groove by turning or grinding is liable to reduce the thickness of the wall irregularly, resulting in a consequent irregular working of the furnace. I have, therefore, devised a modified form of construction illustrated in Fig. 40 5, in which a solid carbon rod or plug F, with perhaps a fine hole through the center, to provide for expansion under heat, is inserted between the terminals and the tube. These rods are grooved circumferentially at F' so as to attain at the groove, a temperature equal to that of the tube after allowing 45 for the conduction of the heat away from this point to the terminal. Since the cross-section of the shell of the tube of the dimensions previously stated, is the same as that of a solid rod cut with a diameter of 1-1/2 inches, the groove in this solid rod or plug 50 should, preferably, be of such depth as to give it substantially a diameter of 1-1/4 inches, thus insuring the proper rise in temperature.

55 60 From the foregoing description, it will be plain that the means for supporting the material to be treated may assume the form such as shown in Fig. 3, in which a one-piece construction is shown, or it may assume the form shown in Figs. 2 and 5, which illustrates a three-piece construction, but in any

65 event, I intend by the phrase "supporting means" to include any of the forms shown in Figs. 2, 3 and 5.

70 With the construction described it will be seen that the object of invention and the advantages sought are attained without in any manner interfering with the conventional forms of furnace fittings.

Having thus described my invention, I claim:

75 1. An electric furnace comprising a body adapted to contain the material under treatment, electric terminals, the said body having a conductive wall, conducting means interposed between the terminal and the wall having a resistance sufficient to cause generation of the heat necessary to maintain a temperature in a zone adjacent to said wall as high as that of the wall itself.

80 85 2. An electric furnace comprising a tubular body having a wall of resister material, electric terminals, and rods interposed between but in electrical connection with the resister wall and the electric terminals, said rod having at some portion sufficient resistance to generate the heat necessary to prevent loss, by conduction to the terminals, of the heat generated in the resister wall.

90 95 3. An electric furnace comprising electric terminals, resister means between the terminals for sustaining the material under treatment and for heating the material, and means interposed between the terminals and the resister means having a resistance sufficient to cause generation of the heat necessary to maintain a temperature adjacent to the resister means as high as that maintained by the resister means itself.

100 105 4. An electric furnace comprising electric terminals, resister means between the terminals for sustaining the material under treatment and for heating the material, and means located between the terminals and the heating portion of said resister means having a resistance sufficient to cause generation of the heat necessary to prevent any loss, by conduction to the terminals, of the heat generated in the said resister means.

110 115 5. An electric furnace comprising a heating chamber having resister material in its wall suitable for causing the generation of heat upon the passage of the electric current, electric terminals, and means for conducting the current from the terminals to said resister material comprising a portion having a resistance sufficient to cause the generation of the heat necessary to prevent loss, by conduction to the terminals, of the heat generated in the said resister material.

120 125 6. An electric furnace comprising a tubular body having a wall of resister material, electric terminals, conducting means interposed between the resister wall and each terminal having a resistance sufficient to cause generation of the heat necessary to

prevent loss from the tubular body by conduction to the terminals.

7. An electric furnace comprising electric terminals, supporting means for the material to be treated having conducting walls and electrically connected with the said terminals, the walls of said supporting means being formed so as to effect a greater resistance to the passage of an electric current at 5 points near the terminals than the resistance of the other portions of the said walls.

8. An electric furnace comprising electric

terminals, supporting means for the material to be treated having conductor walls and electrically connected with the terminals, 15 said supporting means being provided with grooves which are adjacent to the terminal members for the purpose described.

In testimony whereof, I hereunto affix my signature in the presence of two witnesses. 20
